UNITED STATES PATENT OFFICE.

JOHN E. SEDERHOLM, OF ST. PAUL, MINNESOTA, ASSIGNOR TO AMERICAN HOIST & DERRICK COMPANY, A PARTNERSHIP COMPOSED OF F. J. JOHNSON AND W. O. WASHBURN, OF ST. PAUL, MINNESOTA.

LIFTING MAGNET.

Application filed February 15, 1926. Serial No. 88,346.

This invention relates to improvements in lifting magnets, the general object of the invention being to produce a cheap and efficient magnet, of the cylindrical case type, wherein there are no joints in the magnetic circuit.

It is well known that when a connection is to be maintained in an electric circuit, the contact between the joined elements must be perfect to prevent localization effects. In a device like a lifting magnet which is subject to hard usage, the parts are of such magnitude and the meeting surfaces of the joined elements are of such area, that joints cannot be properly securely soldered or welded to obtain and maintain perfect contact. This is particularly true of magnets having pole shoes, wherein the maintenance of proper contact between the pole shoe and magnet case is practically impossible, inasmuch as pounding action against the shoe breaks the joint, reduces contact and causes localization effects, which materially reduce the efficiency of the magnet.

An object of the invention, therefore, is to construct a cylindrical lifting magnet, without the use of a pole shoe, and to secure and seal the coils within the magnet case without producing a joint in the magnetic circuit, thus eliminating the use of pole shoe structure and attendant localization effects.

Other objects are to obtain a uniform magnetic flux density through the magnetic circuit; to reduce the number of parts; to seal the coils against moisture; to provide non-joint means for securing the coils in the case; to give maximum working surfaces with minimum of size and weight of magnet case or frame; to reduce the weight and size of the device as a whole; to secure brace and reinforce the coils to prevent vibration; and to support a coil retaining plate against breakage, when the magnet is dropped.

Features of the invention include a coil retaining plate and non-joint ring-lock for the same, adapted to secure the plate within a coil-receiving groove and to seal the coils against moisture.

Other features include the manner of supporting the coil retaining plate against breakage and the holding of the coil in fixed spaced non-vibratory positions.

Certain advantages and features of the invention will be disclosed in the descrip-

tion of the drawings, and in said drawings. 55

Figure 1 is a vertical diametric section taken through the coil connector means;

Figure 2 is a plan view of the device viewing the lower or working face, with parts broken away to show the reinforcing 60 and spacing rods for the coil-retaining plate and coils;

Figure 3 is an enlarged detail of the seal and lock device, for the coil-retaining plate; and 65

Figures 4 and 5 are views of the rings.

The numeral 1 designates a soft iron one-piece cylindrical magnet case or frame, having a flat working face 2 and further having a circular coil-receiving and housing groove 70 3, extending inwardly from and at right angles to the working face concentrically with the axis of the cylindrical case. This groove defines and provides an annular or hollow cylindrical flange 4, of substantially 75 uniform magnetic capacity axially and circumferentially of the case, and a central cylindrical boss or post 5, of substantially the same magnetic capacity or cubical content as the flange, or of such cross section 80 as to provide well balanced magnetic capacity relation between flange and boss.

A novel non-joint coil-retaining locking and sealing means is provided in the following manner: The coil groove 3 is provided 85 with outwardly faced circular shoulders respectively 6 and 7, at each side, the shoulders being parallel with each other aligned crosswise of the groove and parallel to the working face of the case or frame. In this 90 case two annular coils respectively 8, 9, are used, which are disposed within and against the bottom side of the groove 3. The combined width of the coils is less than the width of the groove, and a number of brace 95 elements, 10, as posts, are inserted between the coils in circumferential spaced relation and held so spaced by suitable insulating material 13, such as asbestos. The function of these posts is to support a non-magnetic 100 coil retaining plate or shield against breakage when the magnet is dropped. This support is particularly necessary, inasmuch as the width of the annular plate is relatively great, being from twelve to eighteen inches 105 according to the size of the magnet.

The coils are suitably covered with a special sealing compound 11 designed to pre-

vent sweating. The outer or lower faces of the coils are covered with a specially treated asbestos insulation indicated at 12. The depth of the coil groove inwardly from the 5 shoulders is less than the corresponding dimension of the coils so that the outer face of the asbestos insulation 12 is substantially aligned with the shoulders.

Adjacent the shoulders 6, 7, and spaced 10 outwardly therefrom are a pair of opposingly related locking ring receiving grooves 14, 15, one in the flange and one in the boss, receiving steel-retaining rings indicated at 16, 17. These rings are split to facilitate 15 their engagement, and act to sealingly engage and retain a single piece annular coil-retaining member 18 of non-magnetic material, in this instance of manganese steel.

The inner side of the member 18 engages the 20 asbestos insulation 12, and shoulders 6, 7 in a manner to press the coils tightly and hold the same securely sealed within the groove, the inner faces of the retaining rings engaged snugly against the outer surfaces of 25 the member 18, and this member is thus forced inwardly to clamping and sealing position. After proper engagement, the opposing ends of the split portion of each ring is soldered, and the joints are calked as 30 at 20 to close the joints between the ring and plate. Thus the coils are non-vibratorily secured, and sealed, without the use of bolts, and without joints in the magnetic circuits.

35 Connections for the coils may be made in any approved manner but the construction shown is preferred.

The numeral 25 indicates a terminal chamber where the connections are made 40 with the plug terminal. The chamber is closed by cap plate 26 suitably held by bolts 27, and through this cap plate extend insulating bushings 28 pressed through the cap plate. Bronze terminal connectors 29, 45 two in number, are provided, one passing through each bakelite bushing. The upper ends of these members are split for obtaining a frictional connection with the cable terminals, when the same are plugged in. 50 Flexible terminal leads 30 connect the coils with the terminal connectors 29.

55 Numeral 31 indicates a protecting cast steel casing for the terminals, which are held within their bushings by suitable lock nuts 32. The usual chain lugs 34 are provided, three pairs arranged in equi-lateral triangular relation, and projecting upwardly from the top of the magnet.

60 The magnet case is recessed as at 35, which corresponds to the neutral zone of the magnet, the material being thus cut away to reduce the weight of the device, without in any way affecting its lifting capacity.

65 When it is desired to remove the rings for any purpose the ring may be either cut

open by the flame of a blow torch, or by cold chisel, and when repairs have been made and the rings re-inserted, the same are simply again welded and calked to force the metal of ring and plate into sealing engagement. Suitable cooling ribs are indicated at 36. It is to be noted that no flange circumferentially of the working face of the magnet is used, for if it were, part of the field strength would be absorbed or weakened and the lifting capacity of the magnet would be reduced. This would be specially so in handling scrap and pig iron, where only small contacts are made. A very even distribution of force or maximum number 70 of magnetic lines per square inch is therefore essential, and is obtained and maintained in the present device.

75 By substantially insetting the outer surface of the manganese steel plate within the groove, the quantitative capacity of the magnet is somewhat increased, for lifting small articles such as steel shavings or scrap, since a portion of the scrap enters the groove and is held therein by the outermost 80 material when the coils are energized.

85 Advantages obtained by applicant's one-piece non-joint magnet case or frame, are: that the amount of machine work is reduced 90 by two-thirds; no bolts are used which can become loose, mashed or rusted; the lifting capacity remains constant because there is no pole-piece and therefore no hammering action against such piece or joint between 95 pole-piece and case. The coils are quickly 100 and easily assembled or dis-assembled and are retained in water-tight and air-tight, braced condition, thus making for a long life of the device. The active working surface is greater in proportion to the outside 105 diameter than in magnets now in use, and therefore the lifting capacity is increased, without corresponding increase in weight.

Having thus described my invention what 110 I claim as new and desire to secure by Letters Patent is:—

1. A device of the class described, comprising a one-piece cylindrical magnet case having a coil-receiving groove therein, coils within the groove, a non-magnetic retaining 115 member securing the coils, and ring members securing the retaining member in coil-retaining position.

2. A device of the class described, comprising a cylindrical magnet case, a coil-receiving groove concentric with the axis of the case, coils within the groove, a plate within the groove retaining the coils, and ring means abuttingly engaging the walls 120 of the groove and plate, and sealingly securing the plate.

3. A device of the class described, comprising a one-piece cylindrical magnet case of soft iron, having a single concentrically related coil-receiving groove, concentric 125

- with the cylindrical axis of the case, each opposite wall of said groove having a shallow ring-receiving groove, annular coils within the first mentioned groove inset a substantial distance from the working face, a non-magnetic annular member for retaining the coils, and retaining ring elements, engaged within the shallow grooves, for securing the member and coils.
4. A device of the class described, comprising a cylindrical magnet frame, having a concentrically related annular coil groove, locking grooves in the walls of the coil groove, coils within the coil groove, an annular retaining plate for the coils disposed within the coil groove, brace elements between the coil and abutting groove and plate, and retaining and sealing rings within the locking grooves, sealingly engaged with the retaining plate.
5. A device of the class described comprising a one-piece cylindrical magnet case having a flat working face, and having a circular coil groove concentric with the axis of the coil, said groove having outwardly faced circumferentially aligned shoulders spaced outwardly from the bottom of the groove, and further having locking ring receiving grooves adjacent and spaced outwardly from said shoulders, coils within and at the bottom of the first mentioned grooves, a coil retaining member of non-magnetic material engaged against the shoulders and coils spaced outwardly from said shoulders, coils within and at the bottom of the first men-
- tioned grooves, a coil-retaining member of non-magnetic material engaged against the shoulders and coils to secure the coils, and retaining rings engaged within the ring-receiving grooves, clampingly and sealingly engaged against the retaining member.
6. A device of the class described, comprising a one-piece cylindrical magnet case having a flat working face, and having a circular coil groove, extending inwardly from said working face, defining and providing an annular flange of substantially uniform magnetic capacity, and a central cylindrical boss or post having substantially the same magnetic capacity as the flange, said groove having outwardly faced circumferential shoulders at each side aligned with each other in a plane parallel with the working face of the case, locking-ring receiving grooves, adjacent said shoulders, one for each shoulder and spaced outwardly therefrom, coils within the groove inset from the shoulders with their outer faces disposed inwardly from the shoulder, insulating material between the coils and shoulders, an annular retaining ring of non-magnetic material engaged against the shoulders and insulating material to secure the coils, and a retaining ring sealingly engaged within each locking ring groove, and with the face of the non-magnetic annulus.

In witness whereof, I have hereunto set my hand this 10th day of February, 1926.

JOHN E. SEDERHOLM.
